INVENTOR.

BY

Alfred Philippe

UNITED STATES PATENT OFFICE

164,711

BRACELET OR THE LIKE

Alfred Philippe, Scarsdale, N. Y., assignor to Tri-fari, Krussman & Fishel, Inc., New York, N. Y.

Application May 1, 1951, Serial No. 15,034

Term of patent 7 years

(Cl. D45—4)

To all whom it may concern:

Be it known that I, Alfred Philippe, a citizen of the United States of America, residing in Scarsdale, county of Westchester, and State of New York, have invented a new, original, and ornamental Design for a Bracelet or the like, of which the following is a specification, reference being had to the accompanying drawing, forming part thereof,

Fig. 1 is a top plan view of a bracelet or the like showing my new design.

Fig. 2 is an edge view thereof.

I claim:

The ornamental design for a bracelet or the like, substantially as shown.

ALFRED PHILIPPE.
